UNITED STATES PATENT OFFICE.

MARJORIE COLE, OF QUINCY, MASSACHUSETTS.

DESIGN FOR A TEXTILE FABRIC OR SIMILAR ARTICLE.

Application filed December 11, 1926. Serial No. 20,028. Term of patent 7 years.

To all whom it may concern:

Be it known that I, MARJORIE COLE, a citizen of the United States, residing at No. 52 Whitney Road, Quincy, in the county of Norfolk and State of Massachusetts, have invented a new, original, and ornamental Design for Textile Fabrics or Similar Articles, of which the following is a specification, reference being had to the accompanying drawing, forming a part thereof. The figure is a plan view of a textile fabric or similar article showing my new design.

I claim:

The ornamental design for a textile fabric or similar article as shown.

December 6, 1926.

MARJORIE COLE.
